UNITED STATES PATENT OFFICE.

GUSTAV GOLDMAN, OF BALTIMORE, MARYLAND.

DESIGN FOR A COAT-PAD.

SPECIFICATION forming part of Design No. 32,558, dated April 17, 1900.

Application filed February 27, 1900. Serial No. 6,767. Term of patent 7 years.

To all whom it may concern:

Be it known that I, GUSTAV GOLDMAN, a citizen of the United States of America, and a resident of No. 2000 McCulloh street, city of 5 Baltimore, State of Maryland, have invented a certain new and original Design for a Coat-Pad, of which the following is a specification.

My new and original design relates to a coat-pad to be used in the manufacture of garments.

Figure 1 is a plan view of the coat-pad. Fig. 2 is an edge view of the pad.

As shown in the accompanying drawings, my design for a coat-pad consists of a pad 5 crescent-shaped, with a V-shaped portion extending from the inner arc of the crescent.

The leading and material feature of my design consists of a crescent-shaped pad having a V-shaped portion extending from the inner arc of the crescent. 20

Having described my invention, what I claim as new, and desire to secure by Letters Patent, is—

The design for a coat-pad as herein shown and described. 25

Signed by me at Baltimore city, State of Maryland, this 16th day of February, 1900.

GUSTAV GOLDMAN.
